UNITED STATES PATENT OFFICE

139,155

DESIGN FOR A MEASURING INSTRUMENT

John K. Seymour, Royal Oak, Mich.

Application July 31, 1944, Serial No. 114,652

Term of patent 14 years

(Cl. D52—1)

To all whom it may concern:

Be it known that I, John K. Seymour, a citizen of the United States of America, residing at Royal Oak, in the county of Oakland and State of Michigan, have invented a certain new, original, and ornamental Design for a Measuring Instrument, of which the following is a specification, reference being had to the accompanying drawing, forming a part thereof, in which Figure 1 is a perspective view of the measuring instru-

ment showing my new design; Figures 2 and 3 are respectively a side elevation and an edge elevation thereof.

The present design comprises as the principal and dominating feature thereof that portion of the measuring instrument shown in full lines.

I claim:

The ornamental design for a measuring instrument, substantially as shown and described.

JOHN K. SEYMOUR,
